UNITED STATES PATENT OFFICE.

LOUIS FRIED, OF BROOKLYN, NEW YORK.

THIEF SIGNAL.

Application filed June 30, 1922. Serial No. 572,002.

To all whom it may concern:

Be it known that I, LOUIS FRIED, a citizen of the United States, and a resident of the city of New York, borough of Brooklyn, in the county of Kings and State of New York, have invented a new and Improved Thief Signal, of which the following is a full, clear, and exact description.

This invention relates to signals or indicating means for use on automobiles or other vehicles and particularly to a device for indicating whether or not the car has been stolen.

The object in view is to provide a simple and effective construction which may be readily seen and which will indicate that the power is being operated by an unauthorized person.

Another object of the invention is to provide a thief signal device which can be readily seen and which when seen will present a breach of police regulation.

A still further object is to provide an improved construction which may be easily set to an operated or locked position or moved to an inoperative position.

In the accompanying drawings:—

Figure 1 is an elevation of a license plate together with a signal device embodying the invention.

Figure 2 is a fragmentary horizontal sectional view through Figure 1 approximately on line 2—2.

Figure 3 is a vertical sectional view through Figure 1 approximately on line 3—3.

Figure 4 is a view similar to Figure 1 but showing a modified form of the invention.

Figure 5 is a sectional view through Figure 4 approximately on line 5—5.

Figure 6 is a view similar to Figure 4 but showing another modified form of the invention.

Figure 7 is a view similar to Figure 1 disclosing a modified construction to that illustrated in Figure 1.

Figure 8 is a fragmentary sectional view through Figure 7 on line 8—8.

Figure 9 is a view similar to Figure 4 but disclosing a modified construction thereof.

Figure 10 is a view similar to Figure 6 but disclosing a modified construction to the construction shown in Figure 6.

Referring to the accompanying drawings by numeral, 11 indicates a frame or hous-

ing of any desired kind which may be provided with a transparent covering or may be left open. The housing or casing 11 is designed to carry a license plate 12 which is necessary for an automobile to have. In 60 constructing the device according to the present invention, it is aimed to provide means for presenting a cancellation of the license plate or some other important or 65 essential part of the machine or attachment so as to indicate to everyone that the vehicle is being used without proper authority.

The embodiment of the invention disclosed in the accompanying drawings presents means for cancelling the license number which is, of course, very prominent and is one of the things first observed by a 70 police officer. The housing or casing 11 75 may be of any desired kind and is preferably open at the bottom. This housing carries a license 12 which is seen through the front opening 13. The casing 11 is longer than the license plate so that the 80 lazy tong cancelling construction 14 may be collapsed in the end 15 or distended to form cancelling members as shown in Figure 1. When the lazy tong structure 14 is in its outer or cancelling position, the hook 85 16 extending from part of the lazy tongs is interlocking with the hook or locking bolt 17 and the lock 18. It will be understood that the lock 18 and the connection thereof with the lazy tongs 14 may be of 90 any kind which will firmly lock the parts in distended position as shown in Figure 1. Certain of the bars of the lazy tongs 14 are provided with extensions 19 which extensions project through the open bottom of 95 the casing 11 and present hand-holds whereby the lazy tongs may be readily collapsed whenever the lock 18 has been moved to an unlocked position. Preferably, this lock is of such a structure that when the lazy 100 tongs are moved from the dotted position shown in Figure 1 to the full line position, they will automatically snap into proper interlocked engagement with the hook 16. A resilient clip 20 is secured to one of the 105 bars of the lazy tongs, said clip being substantially U-shape and having a depressed portion 21 forming a small button on the opposite side whereby when the lazy tongs are collapsed as shown in dotted lines in 110 Figure 1, clip 20 will straddle the front wall of the end 15 and the button formed

by the depression 21 will snap into the depression or aperture 22 and resiliently and yieldingly lock the lazy tongs against movement.

5 In case an unauthorized person uses the automobile to which the lazy tongs 14 are secured and said lazy tongs are in the position shown in Figure 1, they will immediately attract the attention of the general public 10 and also of the police officers because when in this position they will indicate that the car has been stolen or is being used in an unauthorized manner. When a rightful owner parks his car he may move the lazy tongs to the position shown in Figure 1 without breaking police regulations as the license plate may be readily inspected by a 15 police officer whenever necessary, the numbers being merely cancelled and not covered. 20 In Figures 4 and 5, a modified construction is shown wherein the cancellation members consist of bars 23 and 24, said bars having apertured ends through which the 25 guide rods 25 and 26 extend. These bars could be made integral or could be rigidly secured together but preferably are made independent and spaced by suitable spacing sleeves 27 and are also spaced from the top of the casing 11' by spacing sleeves 28. The 30 bar 23 is provided with means interlocking with the lock 18, said means and said lock being of any desired construction and provided with a proper lock for holding the bars 23 and 24 in the position shown in 35 Figure 4. When the lock 18 has been moved to an unlocked position, bars 23 and 24 will drop downwardly into the space back of the lower panel 29 and supported slightly above the bottom of the casing by the plate 30 40 rigidly secured or formed integral with the bar 23. This plate presents a hand-hold for raising and lowering the bars whenever desired as well as a support for the bars when stored in back of the panel 29. 45 In Figure 6 a modified construction is disclosed to that shown in Figure 4, said modification consisting merely in providing a single bar 31 instead of the two bars 23 and 24. Aside from this modification the 50 construction is identical with that shown in Figure 1 and will, therefore, need no additional description.

In Figure 7 a modified construction is disclosed to that illustrated in Figure 1. 55 The construction of these two figures is identical in some respects so that only the additional structure will be described. In the construction shown in Figure 1, the end bars 14' and 14'' of the lazy tongs are provided with slots 32 and 33 through which the supporting and guiding pins 34 and 35 extend while in the structure shown in Figure 7, the bars 14^a and 14^b are provided with slots similar to that just described and 60 in addition with extensions 36 and 37, said

extensions having suitable apertures for receiving the ends of springs 38 and 39, said springs having their opposite ends connected at 40 and 41 to the casing 11. These springs continually act to distend or force 70 outwardly the lazy tongs 14 so that they will occupy the position shown in full lines in Figure 7. By reason of the action of these springs, the clip 20 shown in Figure 1, would not hold the lazy tongs collapsed 75 and, consequently, a special construction is provided as shown in Figure 8.

This construction consists of a spring pressed hook 42 adapted to snap over the end 43 of the bar 14^a. A push rod or pin 44 is provided in the casing 11 and extends to a convenient point whereby the operator may merely press this pin inwardly against the action of the spring 45, and release the lazy tongs whereby the springs 38 and 39 85 will project the lazy tongs to an outer or operated position with the hook 16 interlocking with the bolt of the lock 18.

In Figure 9 a modified construction is presented which is similar to Figure 4 but 90 which has in addition springs 46 and 47 continually acting to hold the bars 23 and 24 in their operated or cancelling position. When it is desired to move the bars 23 and 24 downwardly in back of the panel 29 in 95 this form of the invention, the bar 24 is moved past the spring pressed hook 48 which hook snaps over bar 24 and locks the parts in a lowered position. When it is desired to use the bars 23 and 24, the pin 100 29 is pressed inwardly for releasing the hook 48 and the springs 46 and 47 will immediately move the cancelling bars 23 and 24 to their upper or operated position.

In Figure 10 an additional modified form 105 of the invention is shown which is similar to Figure 6 but the bar 31 is raised by suitable springs 50 and 51. This bar is held in its locked position by hook 48 which may be released by pressing the pin 49 similar 110 to the structure shown in Figure 9. The constructions shown in Figures 9 and 10 are provided with plates 30 which act as hand-holds and also as means for limiting the 115 downward movement of the respective cancelling bars.

What I claim is:—

1. The combination with a license plate for automobiles and other vehicles, of a cancelling member adapted to be moved 120 across the numbers of the license plate without obscuring the same, and means for locking said cancelling member against movement.

2. In a thief signal, the combination with 125 a license plate, of lazy tongs adapted to be extended across the license plate for cancelling the numbers without obscuring them, and a lock for locking the lazy tongs in cancelling position.

3. In a thief signal of the character described, the combination with a license plate, of a casing enclosing said license plate having an opening through which the license plate may be seen, lazy tongs mounted in one end of said casing and normally collapsed to a position out of line with said opening, said lazy tongs being distensible across said opening for presenting cancelling means for 10 said numbers, and a lock for locking said lazy tongs against movement when positioned across said numbers in cancelling position.
4. In a thief signal of the character described, the combination with a license plate, of a casing enclosing said license plate and provided with an opening through which the license plate may be seen, lazy tongs mounted in said casing adapted to be collapsed to a position at one end of the casing when not in use and to be distended across said license plate when in use, a lock for locking the lazy tongs in distended position, and means extending from the lazy tongs to a point exterior of the casing for presenting hand-holds for moving the lazy tongs to either a collapsed or distended position.
5. In a thief signal of the character described, the combination with a license plate, of a casing therefor having an opening
- through which the license plate may be seen, lazy tongs mounted in one end of the casing and adapted to normally be collapsed at said end but capable of distending across 35 said license plate, a clip carried by said lazy tongs adapted to engage part of said casing for holding the lazy tongs in a collapsed position, and a lock for locking the lazy tongs in a distended position. 40
6. In a thief signal device, the combination with a license plate, of a casing surrounding said license plate and having an opening through which the license plate may be seen, lazy tongs mounted in one end of 45 the casing and normally collapsed in said end but capable of distension across said license plate, a lock for locking the lazy tongs in distended position, and spring means acting on the lazy tongs to collapse 50 the same when the locking means have been moved to an unlocked position.
7. In a thief signal of the character described, the combination with a license plate, of cancelling means normally arranged adjacent said license plate and capable of movement across said license plate without obscuring the numbers thereon, and means for locking the cancelling means either in cancelling position or out of cancelling position. 55 60

LOUIS FRIED.
